Primary Examiner — Rosemary K Tarcza*Assistant Examiner* — Sanjeev Paul(74) *Attorney, Agent, or Firm* — Joe Zheng(57) **CLAIM**

I claim the ornamental design for a handset, as shown and described.

DESCRIPTION

FIG. 1 is a front perspective view of a handset showing my new design;

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken line showing on the handset is included for the purpose of illustrating only and forms no part of the claimed design.

“Snail” shown in the drawing disclosure is a registered trademark of Suzhou Snail Electronic Co. Ltd., Suzhou, Jiangsu, China
